UNITED STATES PATENT OFFICE.

WILLIAM H. BRISTOL, OF WATERBURY, CONNECTICUT, ASSIGNOR TO THE BRISTOL COMPANY, OF WATERBURY, CONNECTICUT, A CORPORATION OF CONNECTICUT.

VALVE.

Application filed March 2, 1925. Serial No. 12,583.

The invention relates to an automatic air valve for venting air or other non-condensable gases, particularly such as are likely to develop in connection with the operation of systems utilizing steam and wherein it becomes desirable and generally necessary to remove, preferably automatically, the accumulation of said non-condensable gases which have a tendency to collect in some remote portion of the system. The novel valve device is more especially suitable for use in systems wherein the steam utilized is likely to be at high pressures. Under such conditions, the ordinary type of air valve becomes useless, especially in view of the resulting high temperatures to which the valve mechanism is exposed.

It is the object of the present invention to provide a novel valve suitable for operation under these extreme conditions of temperature and pressure and which shall be rugged and simple in construction without sacrificing effectiveness in the removal of the gases. A further object of the invention consists in a positively acting valve with self-cleaning of the valve seat and in which provision is made for affording visual indication of the state of operation, said means at the same time enabling also the valve to be manually or otherwise operated externally to effect discharge of gas.

The nature of the invention, however, will best be understood when described in connection with the accompanying drawings, in which—

Fig. 1 is a front elevation of the valve, with a portion of the casing broken away to disclose the interior.

Fig. 2 is a side elevation thereof.

Fig. 3 is a fragmentary detail longitudinal section; and Fig. 4 is a vertical section, taken on the line 4—4, Fig. 3.

Referring to the drawings, the valve is shown to consist of a body 10 affording a suitable chamber for receiving the gases to be vented and provided with a horizontally disposed inlet 11 for outside connection in the usual manner. The body 10 is preferably of the T type, having an opening 12 disposed at right angles to the axis of the inlet opening 11, which opening, for convenience in assembly has removably secured thereto an extension piece 13 adapted to be closed by a plug 14. The latter has sol-

dered or otherwise secured thereto the actuating member for the valve, the same being shown as a thermostatic device such as a bi-metallic strip 15. As is well understood, such strip will be affected by differences of temperature to provide a slight movement substantially at right angles to its length, that is to say, the strip is to be so located that its free end will move substantially in the axis of the inlet 11. The free end thereof has, furthermore, secured thereto a valve stem 20 mounted substantially co-axially with the horizontal axis of the valve body or inlet 11 thereof, suitable adjusting nuts 21 being fitted over the threaded portion of the stem and located upon opposite sides of the end of the member 15 to insure the proper location of the stem axially.

The latter is provided intermediate its ends also with an enlargement, as a spherical portion or ball 22; and the said ball 22 is designed to fit a valve seat or cavity 23 provided in the inner face of the plug 24. The latter is designed to close an opening 25 which is disposed in the valve body opposite the inlet opening 11 and coaxial with respect thereto. The said plug, moreover, is bored axially thru to receive an extension 26 of the valve stem, which extension is designed to fit thru the bore of the plug with a slight clearance provided therebetween. Axial movement of the valve stem, due to the influence of temperature variations upon the strip, will thus cause the ball 22 to seat or unseat itself in the said seat 23 to seal or open respectively the outlet thru the plug 24. At the same time, such reciprocatory movement imparted to the extension 26 will serve to keep the valve seat clean and the opening clear at all times—insuring the venting of the gases from the valve, and which will occur until steam reaches the bi-metallic strip 15 to cause same thereby to close again the valve at its seat 23.

In the provision of the extension piece 26, furthermore, a ready means is afforded for indicating, by the amount projecting, whether the valve is sealed or open; and, external control of the valve is also afforded thereby as by pressing thereon, so that the valve may at any time be caused to open. The construction set forth is extremely simple and rugged, and the valve is positively

acting and not subject to damage by the comparatively high temperatures and pressures prevailing.

I claim:

6. 1. An automatic valve, comprising a body affording a chamber provided with an inlet and an outlet to the atmosphere, an externally accessible plug closing said outlet and having an axial bore therethrough affording 10 communication between the interior of the casing and the atmosphere and providing a bearing terminating at its inner end in a valve seat, a thermostatically controlled actuating member carried by said valve body, and a valve stem movable by said actuating member and having a valve member thereon adapted to fit the valve seat to seal the valve and an extension fitting the bearing and operating to maintain the same 15 clean as it reciprocates therethrough.
15. 2. An automatic valve, comprising a body affording a chamber provided with an inlet and an outlet to the atmosphere, an exter- 20

nally accessible plug closing said outlet and having an axial bore therethrough affording 25 communication between the interior of the casing and the atmosphere and providing a bearing terminating at its inner end in a valve seat, a thermostatically controlled actuating member carried by said valve body, and a valve stem movable by said actuating member and having a valve member thereon adapted to fit the valve seat to seal the valve and an extension fitting the bearing and operating to maintain the same 30 clean as it reciprocates therethrough, said extension projecting beyond the outer end of said valve plug to afford a visual indication of the position of the valve as well as to allow of manual operation of the valve to 35 unseat the same for effecting discharge of the gaseous contents of the casing.

Signed at New York, in the county of New York and State of New York, this 13th day of February A. D. 1925.

WILLIAM H. BRISTOL.
